(57) **CLAIM**

The ornamental design for a housing for a fire pit, substantially as shown and described.

DESCRIPTION

FIG. 1 is a perspective view of a housing for a fire pit showing our new design;

FIG. 2 is a front view of the housing for a fire pit;

FIG. 3 is a rear view of the housing for a fire pit;

FIG. 4 is a right side view of the housing for a fire pit;

FIG. 5 is a left side view of the housing for a fire pit;

FIG. 6 is a top view of the housing for a fire pit; and,

FIG. 7 is a bottom view of the housing for a fire pit.

The broken line elements in all views are for illustrative and environmental purposes only and form no part of the claimed design.
